ADOLPH PETZOLD, OF PHILADELPHIA, PENNSYLVANIA, ASSIGNOR TO JOHN H. BROMLEY, JOSEPH BROMLEY, AND EDWARD BROMLEY, OF SAME PLACE.

DESIGN FOR A RUG.

SPECIFICATION forming part of Design No. 26,719, dated March 2, 1897.

Application filed January 22, 1897. Serial No. 620,275. Term of patent 7 years.

To all whom it may concern:

Be it known that I, ADOLPH PETZOLD, a citizen of the United States, residing in the city of Philadelphia, State of Pennsylvania, have invented and produced a certain new and original Design for Rugs, of which the following is a full, clear, and exact description, reference being had to the accompanying drawing, forming a part of this specification.

My invention relates to the surface ornamentation of a rug; and it consists of the design therefor, as illustrated in the accompanying drawing, in which it is shown applied to a woven Smyrna rug.

The leading features of the design are a surrounding rectangular border or frame of

leaf-like figures, and within the same, in one corner, an annular frame inclosing a shield bearing a pair of crossed mallets, while the center ground is filled with a representation of growing trees, a tree-stump, and a log against which rests an ax and a mallet.

I claim—

The design for a rug substantially as shown and described.

In testimony whereof I have hereunto affixed my signature this 2d day of January, A. D. 1897.

ADOLPH PETZOLD.
